CLAIM

The ornamental design for a food tray, as shown and described.

DESCRIPTION

FIG. 1 is a perspective view of a food tray showing my new design;

FIG. 2 is a top view thereof;

FIG. 3 is a bottom view thereof;

FIG. 4 is a right side view thereof, the left side being a mirror image thereof; and,

FIG. 5 is a front view thereof, the rear view being a mirror image thereof.
